UNITED STATES PATENT OFFICE.

EDWARD L. WEED, OF PROVIDENCE, RHODE ISLAND, ASSIGNOR TO POTTER & BUF-
FINTON COMPANY, OF PROVIDENCE, RHODE ISLAND, A CORPORATION OF RHODE
ISLAND.

BADGE.

Application filed July 14, 1921. Serial No. 484,742.

To all whom it may concern:

Be it known that I, EDWARD L. WEED, a citizen of the United States, residing at Providence, in the county of Providence and 5 State of Rhode Island, have invented certain new and useful Improvements in Badges, of which the following is a specification.

This invention relates to an improvement in the construction of badges, emblems, 10 charms, or the like, and has for its object to provide such a device more particularly adapted to be used as a pendant for watch chains or neck chains, but it may be attached to rings, cuff buttons or other articles of jewel- 15 elry to be used as an emblem, the device being constructed to house one or more symbols or characters on members which may be moved outwardly to expose the symbol, and back to house or inclose the same in the 20 body of the device.

With these and other objects in view, the invention consists of certain novel features of construction, as will be more fully described, and particularly pointed out in the 25 appended claims.

In the accompanying drawings:

Figure 1 is a front view of my improved emblem partly broken away illustrating the 30 movable symbol-carrying members in different positions.

Figure 2 is a perspective view illustrating the end portion of one of the arms of the cross-shaped emblem.

Figure 3 is an enlarged perspective view 35 showing a detail of one of the emblem-carrying arms.

With reference to the drawings, 10 designates two oppositely-disposed plates which may be formed of any suitable material cut 40 into any desired shape to form the desired emblem or device. In the present instance I form these plates to represent a Maltese cross and I space the plates a short distance apart and support them in spaced-apart relation by narrow walls 11 which 45 serve to close the side edges of the arms of the cross.

In the main or body portion of the emblem it is found desirable to carry a number of 50 symbols or characters and my present invention relates to simple and effective means for mounting such symbols whereby they may be readily exposed when desired and then housed within the body of the main emblem when not to be exposed; and the 55

following is a detailed description of one means by which this result may be accomplished:—

At the ends of one or more of the arms of the cross I have mounted a symbol or emblem-carrying member 12 pivotally mounted at one end 13 between the opposite side plates 10 of the body of the emblem, and on the inner face 14 of this symbol-carrying member I preferably mount an auxiliary symbol or device 15 which may be of any shape and size that will enter the space between the side walls or plates 10 formed to receive it.

The free end of this symbol member is 70 provided with an inturned resilient lip 16 which is adapted to snap over the detent pin 17 located in the edge of the cross arm opposite to that of the pivot pin, whereby when the swinging member is closed this 75 lip will engage this pin and releasably lock the member in closed position.

In order to limit the opening swing of this member 12, I have provided an extending end 18 projecting beyond its pivoting point 80 which end will engage the end 19 of the edge walls 11 to form a positive stop to determine the extent of the opening swing of this member.

I have shown an end plate 21 by which 85 the device may be connected to a support when suspended, but I do not wish to be restricted to the use of this particular portion of the emblem as in some cases it may be dispensed with particularly when the emblem is attached to a ring or secured in other fixed position.

By my improved construction of emblem it will be seen that in addition to the main body portion of the emblem I may readily 95 carry a plurality of other symbols one on each of the arms, if desired, the size and shape of the auxiliary symbols being limited only by the space between the side plates of the arms of the main emblem in which the symbol-carrying members are supported, and by this construction it will be seen that the free end of each of the symbol-supporting members extends beyond the edge walls 100 between the side plates thus positioning them to be readily engaged to be swung to open position to expose the symbol carried thereby.

The foregoing description is directed solely towards the construction illustrated, but I desire it to be understood that I re- 110

serve the privilege of resorting to all the mechanical changes to which the device is susceptible, the invention being defined and limited only by the terms of the appended 5 claims.

I claim:

1. A badge comprising a pair of oppositely-disposed plates shaped to represent the desired insignia and secured together in spaced-apart relation to form a chamber between them, a movable symbol-carrying member for closing the opening between said plates and adapted to be manipulated to expose its symbol and back to house the same 10 in said chamber, a stop for limiting the swinging movement of said member, and a hook carried by said member adapted to engage a pin which connects the spaced arms to secure the said member in closed position, said badge being adapted to be attached to a support.

2. A badge comprising a pair of oppositely-disposed cross-shaped plates secured

together in spaced relation, walls closing the side edges of the cross arms, a symbol-carrying member for closing the openings at the ends of said arms and pivotally mounted between said plates, said members being adapted to be swung out to expose its symbol and back to house the same between 25 said plates, and means on said badge whereby it may be attached to a support.

3. A badge comprising a pair of plates shaped to form a cross and secured together to provide a symbol housing chamber between them, symbol bearing members movably mounted at the ends of the arms of said cross and adapted to be moved out to expose its symbol, means for limiting the opening motion of said members, and a detent for 30 releasably retaining said members in closed position, said badge being adapted to be attached to a support.

In testimony whereof I affix my signature.

EDWARD L. WEED.
